UNITED STATES PATENT OFFICE.

RICHARD E. WALKER, OF ROANOKE, VIRGINIA.

CONVERTIBLE RAILWAY-CAR.

1,344,323.

Specification of Letters Patent. Patented June 22, 1920.

Original application filed August 23, 1919, Serial No. 319,393. Divided and this application filed January 24, 1920. Serial No. 353,674.

To all whom it may concern:

Be it known that I, RICHARD E. WALKER, a citizen of the United States of America, and a resident of Roanoke, county of Roanoke, and State of Virginia, have invented certain new and useful Improvements in Convertible Railway-Cars, of which the following is a full and clear specification.

The object of this invention is to so construct a railway car that it may be readily converted from a car having a flat, closed bottom into a car having a double, inclined bottom leading to a center dump chute, as more fully hereinafter set forth.

15 This application is a division of my pending application Serial No. 319,393, filed August 23, 1919.

In the drawings—

20 Figure 1 is a vertical longitudinal sectional view of the lower part of a railway car provided with my convertible bottom;

Fig. 2 a vertical cross-sectional view showing more particularly the worm-gearing for shifting the bottom sections; and Fig. 3 a 25 detail horizontal sectional view.

Referring to the drawings annexed by reference-characters, *a* designates the two permanent floor-sections, one arranged at each end of the car, and *b* two adjustable floor-sections each extending from one of said permanent sections to the transverse center of the car, these sections serving to complete the floor of the car and being flush with the permanent sections *a* when the car is adjusted for use as a box-car. The inner ends of adjustable sections *b* rest on a transverse beam *c* at the center of the car, and near their outer ends they are each affixed to a rockable shaft *d* suitably journaled in the floor-beams of the car and located under the floor-section *b* and a short distance from its outer end. Each of these sections *b* may be swung upwardly and outwardly toward the end of the car by rock-shaft *d*, and when thus swung over as far as they will go their outer ends rest upon transverse battens *e* affixed to the end-walls of the car, as shown in dotted lines in Fig. 1. This rocking of the shaft *d* is accomplished through the medium of a worm-gear *f* affixed to shaft *d* and engaged by a worm *g* mounted on the

shaft *h* journaled in suitable bearings in the side of the car, said shaft being squared at one end to permit it to be turned by the application of a crank-wrench.

The usual center dump-chute is provided underneath the adjustable sections *b*, this chute consisting of the two oppositely-inclined bottom sections *i* and the two central dump-doors *j*, which latter are adapted to 60 be opened and closed in any suitable manner, desirably by chains *k* and transverse shafts *l*. The inclined bottom-sections *i* do not extend entirely to the inner edges of the permanent sections *a*, but terminate short 65 thereof, leaving a transverse space *m*, which space is closed by the outer end of the swinging section *b* when the same is inverted into the dotted-line position, so that in this inverted position the adjustable section *b* 70 forms virtually a continuation of the permanent chute section *i*, so that each inclined wall of the chute extends continuously from the dump-doors *j* upwardly to the end-wall of the car.

The nature and scope of the invention having been thus indicated and its preferred embodiment having been specifically described, what is claimed as new is:

In a convertible car, a floor-structure embodying permanent floor-sections at the ends of the car, two invertible floor-sections completing the floor of the car, each of these sections being mounted and supported upon a rock-shaft connected to the section at a 80 distance from its outer edge, means for inverting these sections to swing their inner edges upwardly and outwardly to meet the end-walls of the car to thus convert them into downwardly-inclined chute-sections, a 85 centrally-arranged chute whose inclined walls extend upwardly and outwardly toward but terminate short of the respective rock-shafts, so that when said floor-sections are inverted their outer edges will meet the 90 top edges of said inclined walls and thus convert said floor-sections into virtual extensions of said inclined walls.

In testimony whereof I hereunto affix my signature.

RICHARD E. WALKER.
